MEAD HEDGLON, OF SYRACUSE, NEW YORK, ASSIGNOR TO DE BANKS M. HENWARD, JR.,
OF SYRACUSE, NEW YORK

OIL CHANGING SYSTEM

Application filed April 2, 1930. Serial No. 441,068.

This invention relates to an improved oil changing system for internal combustion engines of automobiles, airplanes, and the like, and has for its object to provide novel and simple means for drawing off the used oil from the engine crank-case or base. A further object is to equip the crank-case with a permanent drain pipe to take the place of the usual gravity drain opening in the bottom of the case, the discharge end of said pipe being disposed above the level of the oil body and being accessible by simply raising the hood of the engine. A further object is to provide a main transmission line which is arranged to be instantly connected with said drain pipe, and by which the used oil may be conducted to a transparent inspection cylinder, where the quantity of the oil may be observed, and wherein facilities are provided for testing the used oil to determine its further lubricating value, the said main transmission line including a reversible valve and also a reversible siphon injector or pump by which the crank-case may be quickly and effectively drained and afterwards recharged with the used oil, if desired, and said line being equipped with means for consigning the worthless used oil to a sump or other waste receptacle. A further object is to provide a series of tanks for containing new oil of different grades, the said tanks being equipped with individual valves, by which the different grades of oil may be selectively supplied to the crank-case, by means of an auxiliary transmission line that may include a one-way pump, which is arranged to connect directly with the reversible valve of the main line for effecting the recharging of the crank-case with fresh oil, without disturbing the other parts of the main line, the said auxiliary line adapted to be utilized for pumping kerosene or other washing fluid into the crank-case for cleansing said case, said washing fluid being finally withdrawn from the crank-case via the main transmission line, and consigned to the waste receptacle, as described. And a further object is to provide a system of this class, whereby automobiles may be driven into filling stations or garages, within con-

venient reach of the oil changing mechanism, and have the oil drawn off and tested, the crank-case washed, and the oil changed without requiring the automobile to be elevated, or inconveniencing its occupants.

The various features and parts of the invention will be understood from the detailed description which follows, and by reference to the accompanying drawing, in which—

Figure 1 is a broken diagrammatic view partially in elevation and partially in vertical longitudinal section, showing a fragment of an internal combustion engine base, to which my improvement is applied. Fig. 2 is a central vertical longitudinal section of the reversible air-controlled injector or pump, of Fig. 1, but showing the valve reversed, as compared with the showing in Figs. 1 and 4. Fig. 3 is a top plan view of the valve by which new or old oil may be selectively transmitted relatively to the engine base. And Fig. 4 is a central horizontal section, taken on line 4—4 of Fig. 1, showing the reversible pump adjusted for draining the used oil from the base.

In the drawing, 2 represents an ordinary crank-case or base of an internal combustion engine, in which is usually disposed a body of lubricating oil, as 3, to be distributed to certain of the internal working parts of the engine, by the well-known splash system. The bottom of the base 2 is usually fitted with a drain opening as 4, by means of which the used oil 3 may be drawn off, said opening usually being normally closed by a screw plug (not shown). In the present showing, the plug is dispensed with and in lieu thereof a drain pipe, as 5, that serves both as a draining and filling medium is permanently installed in the base, one end 5' of said pipe being inserted through the opening 4 and preferably extends upwardly a considerable distance (see Fig. 1), in order to initially spray the inflowing oil over the crank-shaft, piston-rods, and pistons. Outside of the base 2, the pipe 5 is bent and extended upwardly a suitable distance above the end 5', its top end 5a being fitted with a pin, as 5b, which passes through the pipe diametrically, and comprises one member of an ordinary bayonet

coupling. 6 represents a two-way valve which is partially rotatable in an annular casting 6', by a handle 6a. The valve 6 connects with the top 5a of the drain pipe, by means 5 of an elbow pipe 6b, which comprises the second member of bayonet coupling, and whose enlarged free end is formed with slots 6x that engage the pin 5b. The valve casing 6' is formed with two nozzles, as 6c—6d, by 10 which the oil may be transmitted from, as well as toward the engine base, or new oil may be substituted for the used oil by the manipulation of handle 6a, as may be understood by consulting Fig. 1. Beyond the valve 15 6 is disposed an air pump or siphon injector, as 7, which may be connected with said valve, by means of a flexible pipe or hose, as a. The injector 7 comprises a rotatable member 7', which is enclosed in a casing 7a, and which 20 may be controlled manually, by a handle 7b, the said member being formed with a relatively large diametrical opening 7c that may be connected with oppositely facing nozzles 7d—7e. Within the passage 7c, is disposed 25 another nozzle, as 7f, which is movable with the member 7', and constitutes the outlet for the compressed air, by which the siphoning or injecting work is effected, the air pressure being supplied by a pipe 7x. In Figs. 1 and 4, 30 the member 7' is positioned to withdraw the used oil 3 from the crank-case 2, and in Fig. 2 the said member is shown reversed for injecting oil or other fluid into the said base. Obviously, the injector 7 may be dispensed with 35 and any of the well-known gear pumps may be employed, provided that the latter is operated by a reversible motor (not shown). The used oil drawn from the crank-case 2, may be carried by a pipe 8 to a transparent 40 inspection reservoir or tank 9, the said oil may however, be allowed to gravitate into a waste sump (not shown), by means of valve 10, which is located in the pipe 8. The inspection tank preferably comprises a clear 45 upright glass cylinder 9', which is supported by a perforated base 9a through which the farther end of pipe 8 passes, the latter preferably extending above the middle of the cylinder and discharging the mixture of oil and 50 air against an inverted cup-shaped baffle 9b, which tends to agitate the mixture and allow the air to filter upwardly and escape through a vented top cap 9c, which facilitates filling of the tank, and obviates the danger of the oil 55 escaping with the air. Externally the cap 9c, is fitted with a similar baffle, as 9d, which further tends to prevent the free escape of the oil to the atmosphere. The transparent cylinder 9' enables the operator to inspect the 60 oil 3, and having a scale denoting liquid measurements enables him to accurately determine the quantity withdrawn from the crank-case 2. The operator may, if he desires, make a test of the quality of the used 65 oil, by drawing off a small sample by means of a tap 9e, through which the oil may gravitate from the bottom of the cylinder 9, and in case the test shows the oil to be still suitable for lubricating the working parts of the engine, the said oil may be returned to the 70 crank-case through the same transmission line, by simply reversing member 7' of the injector, as shown in Fig. 2. In case the used oil is found to be unfit for further lubrication, the valve 10 may be opened and the said 75 oil may be allowed to gravitate from the tank 9 to a waste receptacle, as explained. The tank 9 is shown mounted upon a bench or platform 12, which may also support additional tanks, as 13—13', which may be filled 80 with oils of different quality, as heavy, medium and light oil. Each tank 13 is provided with a gravity discharge pipe, as 13a, and each pipe is preferably fitted with an ordinary cock 13b to facilitate the selective dispensing 85 of the different grades of oils. The tanks 13 may be of any suitable capacity, and may be graduated like tank 9, to indicate definite measurements of oil. Additional tanks for containing kerosene or other washing liquids 90 suitable for flushing and cleansing the crank-case 2, may be provided and connected to an auxiliary transmission line, comprising a horizontal pipe 14, which is provided at intervals with T's 14', by which the individual 95 pipes 13a may connect with said line. Upon the forward end of pipe 14 is mounted a pump or injector 15, preferably having a one-way action, for drawing the oils or other liquids from the line 14, and discharging the 100 same via a hose or other flexible extension, as 15' into valve 6, the hose 15' preferably telescoping the nozzle 6d, and when the member 6 is rotated by the movement of handle 6a from the full line to the dotted position of 105 Fig. 1, the new oil from the tanks 13 may be forced into the crank-case 2, as explained. The pump 15 may be of any suitable type, 110 details not herein shown, and said pump may be operated by compressed air, which may be supplied by a pipe 16, in which is located a throttle valve 16'. The pipes 5 and 8 are preferably provided with a number of small perforations as 5c and 8' to facilitate the complete 115 draining of the crank-case 2 and the tank 9.

Having thus described my invention, what I claim, is—

1. An oil changing system for use with an internal combustion engine, including a distant inspection tank, an oil transmission line connecting said crank-case with said tank, said line comprising a draining and filling pipe connected to the crank-case and communicating with its interior, reversible siphon means in said transmission line communicating with said tank, a two-way valve interposed between said pipe and said siphon means, said valve having two nozzles, one of said nozzles communicating with said siphon means,

- means to adjust said valve to enable said siphon means to transfer the used oil from the crank-case to said tank, means to adjust said siphon means to recharge said crank-case with said used oil, a source of fresh oil supply, an auxiliary transmission line adapted to connect said fresh oil supply with the second nozzle of said valve for charging the crank-case with unused oil by the reversing of said valve, and means for forcing the unused oil through said auxiliary transmission line. 5
2. An oil changing system, for use with the crank-case of an internal combustion engine and a used-oil inspection tank, including a transmission line to conduct the used-oil from the crank-case to said tank comprising a drain pipe permanently mounted on the crank-case, a two-way valve communicating with said pipe, said valve having two nozzles, a siphon injector communicating with one of said nozzles adapted to transfer the used-oil from the crank-case to said tank, means to reverse said injector to recharge the crank-case with 10 said used oil, a source of new oil, and an auxiliary transmission line, said auxiliary line communicating with said new oil source and a second nozzle of said valve, and said auxiliary line including a pump adapted to transfer the new oil via said valve and said pipe into the crank-case. 15
3. An oil changing system for use with the crank-case of an internal combustion engine, including a permanent drain pipe, a two-way valve communicating with said pipe and having two nozzles, a reversible oil pump communicating with one of said nozzles, a vented inspection reservoir communicating with said pump, means to adjust said valve and said pump to effect the transfer of the used oil from the crank-case to said reservoir, means to reverse said pump to recharge the crank-case with said used oil, means interposed between said pump and said reservoir to divert said used oil to a waste receptacle, a series of tanks to contain fresh oil, and an auxiliary transmission line connecting said series of tanks with the second nozzle of said valve for charging the crank-case with fresh oil when said valve is reversed. 20
4. An oil changing system for use with the crank-case of an internal combustion engine including a permanent draining and filling pipe, an oil changing system including a two-way valve adapted to be coupled to said pipe and having two nozzles, an inspection reservoir, a main transmission line to connect one of said nozzles with said reservoir, a series of tanks to contain new oil, an auxiliary transmission line connecting said series of tanks with the second nozzle of said valve, a reversible pump disposed in said main line between said valve and said reservoir adapted when properly adjusted to transfer the used oil to 25 said reservoir, a single action pump disposed in said auxiliary line adapted to selectively transfer fluid from said series of tanks to the crank-case by the reversing of said valve, and means to divert the contents of the crank-case to a waste receptacle. 70
5. An oil changing system, for use with the crank case of an internal combustion engine having a permanent draining and filling pipe, including a distant inspection tank, an oil transmission line connecting said pipe and tank, a two-way valve having a pair of nozzles disposed in said line and connected to said pipe, a siphon injector interposed between one nozzle of said valve and said tank adapted in one position to transfer the used oil from the crank case to said tank to enable the operator to inspect and test said oil, and in another position for transferring said used oil from said tank to said crank case, and means connected to the other of said nozzles of said valve for conducting new oil to the crank case. 75
6. An oil changing system, for use with the crank case of an internal combustion engine, including an inspection tank, an oil transmission line communicating with the interior of said crank case, a two-way valve tapping said pipe, said valve having two nozzles, a reversible injector communicating with one of said nozzles adapted to siphon the used oil from the crank case and to inject said oil into said tank, means to reverse said injector to transfer said oil from the tank to the crank case, means interposed between the injector and the tank to divert said oil from the transmission line to a waste receptacle, and means connected to the other of said nozzles of the two-way valve for conducting new oil into the crank case. 80
7. An oil changing system for use with an engine crank case, including an inspection tank, means for conducting used oil from the crank case to the tank, means for conducting new oil to the crank case, a casing common to and connected to each of said conducting means and having a two-way valve for selective registration with either of the conducting means, a single means leading from said casing for communication with the crank case, and through said valve with either of the conducting means, means associated with the used oil conducting means for selectively draining the oil from the tank or for permitting the oil to be returned to the casing and through the latter into the crank case, and means in the used oil conducting means for selectively drawing off oil from the crank case and for forcing same into the tank or for returning oil from the tank back into the crank case. 85
8. An oil changing system for use with an engine crank case, including a receiver, means for conducting used oil from the crank case to the receiver, means for conducting new oil to the crank case, means associated with 90
9. An oil changing system for use with an engine crank case, including a receiver, means for conducting used oil from the crank case to the receiver, means for conducting new oil to the crank case, means associated with 95
10. An oil changing system for use with an engine crank case, including a receiver, means for conducting used oil from the crank case to the receiver, means for conducting new oil to the crank case, means associated with 100
11. An oil changing system for use with an engine crank case, including a receiver, means for conducting used oil from the crank case to the receiver, means for conducting new oil to the crank case, means associated with 105
12. An oil changing system for use with an engine crank case, including a receiver, means for conducting used oil from the crank case to the receiver, means for conducting new oil to the crank case, means associated with 110
13. An oil changing system for use with an engine crank case, including a receiver, means for conducting used oil from the crank case to the receiver, means for conducting new oil to the crank case, means associated with 115
14. An oil changing system for use with an engine crank case, including a receiver, means for conducting used oil from the crank case to the receiver, means for conducting new oil to the crank case, means associated with 120
15. An oil changing system for use with an engine crank case, including a receiver, means for conducting used oil from the crank case to the receiver, means for conducting new oil to the crank case, means associated with 125
16. An oil changing system for use with an engine crank case, including a receiver, means for conducting used oil from the crank case to the receiver, means for conducting new oil to the crank case, means associated with 130

each of said conducting means for selectively causing used oil to be conducted through the used oil conducting means to the receiver or for causing the new oil to be conducted to the crank case, means for selectively drawing off the oil from the crank case and through the used oil conducting means to the receiver, or for forcing the used oil through the first named selective means back into the crank case, and means for forcing new oil through said new oil conducting means and through the first named selective means into the crank case.

In testimony whereof I affix my signature.
